UNITED STATES PATENT OFFICE.

DONALD A. MCKAY, OF ELNORA, ALBERTA, CANADA.

COMBINATION-PADLOCK.

1,295,543.

Specification of Letters Patent.

Patented Feb. 25, 1919.

Application filed November 12, 1915. Serial No. 61,132.

To all whom it may concern:

Be it known that I, DONALD A. MCKAY, a subject of the King of Great Britain, residing at Elnora, in the Province of Alberta and Dominion of Canada, have invented certain new and useful Improvements in Combination-Padlocks, of which the following is a specification.

This invention relates to locks and more specifically to an improved form of keyless padlock.

The object of this invention is to provide a keyless padlock in which the movement of the shackle thereof depends upon the relative position of a plurality of rotatable disk tumblers.

A still further object of this invention is to provide a device of the kind above described, that is simple in construction, efficient in operation, and consists of a minimum number of parts.

With these and other objects in view, this invention resides in certain novel features of construction, combination and arrangement of parts, as will be hereinafter more fully described and claimed and shown in the accompanying drawings wherein:

Figure 1 is a longitudinal sectional view of the improved device, the shackle thereof being locked against movement;

Fig. 2 is a top plan view of the device with one of the plates thereof removed;

Fig. 3 is a fragmentary view in elevation of a portion of the lock.

Referring to the parts by reference numerals, this padlock comprises a pair of plates 10 and 11 that are suitably secured by the means 12. The plate 10 is provided with a plurality of recesses for the reception of

the disk tumblers 13 and running from these recesses to receive the disk tumblers 13 are openings through which the shafts 14 are positioned. These shafts 14 are secured fast to the disk tumblers 13 and their outer ends

are provided with finger engaging knobs 15. Secured fast to each of the shafts 14, adjacent the outer face of the plate 15, are dials 16 that have thereon a plurality of suitable numerals that are adapted to be alined with a suitable mark as indicated by the numeral 17 in Fig. 3, thus by the movement of the shafts 14, the disk tumblers 13 are suitably controlled.

The plate 10 has a suitable depression 18 located centrally thereof, the same communicating with the several recesses into

which the disk tumblers 13 are positioned. A recess 20 is centrally located in the plate 10 and communicates with the depression 18, and a cavity 19, the latter being formed in the plate 11.

As is clearly shown in Fig. 2 each of the disk tumblers 13 is provided with a cut-out portion 21. A substantially U-shaped shackle 22 is provided, one of its arms, as indicated at 23, being slightly longer than the other. A master tumbler 24 is secured on said arm adjacent its terminal. A polygonal cavity is provided in the plate 10 into which the polygonal shaped end of the arm 23 is seated, as is clearly shown in Fig. 1. The arm 24' of the shackle 22 is mounted in a corresponding opening in the plate 11.

When the device is locked, that is, when the shackle 22 is held from movement relative to the plates 10 and 11, the disk tumblers 13 and 24 are positioned as shown in Figs. 1 and 2, that is, portions of the tumblers 13 overhang portions of the tumbler 24 and as the tumbler 24 is secured fast to the arm 23 of the shackle 22, the said shackle is held from movement. The lock may be readily released by any person knowing the combination since it is necessary merely to rotate the knobs 15 thereby bringing the combination characters on the dials 16 into alinement with the corresponding combination characters represented at 17. By this operation the cut out portion 21 in each of the tumblers 13 is moved adjacent the periphery of the tumbler 24, thereby permitting the free movement of the master tumbler out of the cavity 18 into the depression or cavity 19 in the plate 11, thus moving the shackle as is indicated in dotted lines in Fig. 1.

It is obvious that minor changes may be made in the form and construction of this device, without departing from the material parts thereof. It is therefore not wished to confine the invention to the exact form and construction herein shown and described but it is wished to include all such as properly come within the scope claimed.

What is claimed is:

1. A padlock including two plates contiguously arranged and provided with communicating recesses, a shackle, one end of which is arranged through one of said plates and equipped with a master tumbler which normally seats in the recess of the opposite plate, and a plurality of locking tumblers arranged above the master tumbler

to retain the latter from movement, and means to operate the locking tumblers for permitting movement of the master tumbler thereapast and into the recess in the first 5 said plate.

2. A padlock including top and bottom plates secured together and provided with central communicating recesses, a shackle of U-shape having one of its ends inserted 10 through the top plate and terminating in the recess of the bottom plate and being equipped with a master tumbler which fits in said recess, a plurality of locking tumblers

arranged in said bottom plate with portions of their periphery arranged over the periphery of the master tumbler, portions of said locking tumblers being removed to permit movement of said master tumbler into recess in said upper plate. 15

In testimony whereof I affix my signature 20 in presence of two witnesses.

DONALD A. MCKAY.
